UNITED STATES PATENT OFFICE.

JOSEPH H. CAMPBELL, OF NEW YORK, N. Y., ASSIGNOR OF THREE-EIGHTHS
TO CHARLES H. CAMPBELL AND JAMES McLAIN, BOTH OF SAME PLACE.

VAPOR-ENGINE.

SPECIFICATION forming part of Letters Patent No. 337,373, dated March 9, 1886.

Application filed July 27, 1885. Serial No. 172,777. (No model.)

To all whom it may concern:

Be it known that I, JOSEPH H. CAMPBELL, a citizen of the United States, residing at New York, in the county of New York and State 5 of New York, have invented certain new and useful Improvements in Vapor - Engines, of which the following is a specification, reference being had therein to the accompanying drawing.

10 My present invention is designed as an improvement on the method of utilizing aqua-ammonia as motive power in engines shown, described, and claimed in an application for a patent filed by me June 11, 1885, Serial No. 15 168,839.

My invention therefore consists in devices for driving off the ammoniacal vapor from the boiler and permitting it to escape below the surface of the liquid in the reservoir, thereby 20 securing the absorption of the vapor, and consequently the heat developed by the absorption, to superheat the vapor in the reservoir.

My invention consists, further, in the arrangement of pipes and valves leading from 25 the pump to the reservoir and boiler, that the liquid may be delivered in either, and thereby the tension of the vapor controlled or regulated.

My invention consists, further, in devices for 30 heating the cylinder and superheating the working-vapor therein by bringing the exhaust-vapor of the engine in contact with a cooled weak solution of the liquid around the cylinder, and to correspondingly cool the liquid heated by the absorbing process prior to 35 its entrance into the absorber, the cylinder thus acting as an auxiliary to the absorber.

My invention consists, further, in certain details of construction, which will be fully described hereinafter, and pointed out in the 40 claims.

In the drawing I have shown a longitudinal view, partly in section, of the boiler, reservoir, cylinder, cooler, absorber, pump, and 45 valves which constitute my machine or plant, the several parts and functions of which I will now describe in detail.

A indicates the boiler, which may be of any suitable or desirable construction, and it is 50 connected to and communicates with the reservoir B by means of the pipe C, said pipe

being provided with a plug-valve, a, and is designed to transfer the aqua-ammonia from the boiler to the reservoir, or vice versa, according to the required pressure or tension. 55

B is the dynamical reservoir and superheater, the upper portion of said chamber being the superheater and the lower portion the dynamical reservoir.

D is a pipe leading from the upper portion 60 or vapor-space of the boiler to the reservoir B, said pipe entering through the bottom of the reservoir and extending up into the same, where it is bent into a return-curve, so as to discharge the vapor below the surface of the 65 liquid contained in the reservoir. The pipe D is provided with a check-valve, c, to prevent the liquid in the reservoir from being forced back into the boiler when the pressure of the reservoir is in excess of that in the 70 boiler. This valve c opens upward, so as to allow of the free passage of the vapor from the boiler to the reservoir.

The object of discharging the expelled vapor into the reservoir below the surface of the 75 liquid is to comply with the conditions of absorption—viz., bringing the liquid and vapor in contact. If the vapor were discharged above the surface of the liquid in the reservoir, since water will not transmit the radiant 80 heat of steam and the diathermancy of ammoniacal vapor is only 1.1195, (air being 1,) a non-diathermic diaphragm is formed by the heated surface of the liquid, which not only prevents the heat from passing down into the 85 reservoir, but also acts as a barrier to prevent the re-solution of the expelled vapor with the liquid in the reservoir; consequently the heat of absorption is not generated to superheat the vapor in the reservoir. The boiler 90 A is also connected to the reservoir by the pipe E, which extends up into the vapor-space of the reservoir and returns by a series of coils, d, down to or near the water-line, and then straight through the liquid and bottom of 95 the reservoir B.

The object of coiling the pipe E in the vapor-space is to increase its heating-surface to superheat the vapor, so that the tension of the vapor therein contained can be raised to 100 the proper working-pressure without materially changing the temperature of the fluid in

the reservoir; and, furthermore, the liquid in its passage through the coil gives off a certain amount of its heat to the liquid and vapor in the reservoir, thereby becoming partially 5 cooled before entering the cooler F.

The pipe E, after passing through the bottom of the reservoir B, is coiled, as shown at e, said coil being inclosed in a chamber, F, which is supplied with cold water by means 10 of the pipe f. The object of thus cooling the weak solution of aqua-ammonia which passes through the pipe is to restore its absorptive power before it is brought into contact with the exhaust-vapor.

15 The pipe E is provided with a valve, G, of the well-known type of safety-valves, the head of said valve being provided with an elbow-lever, H, having a weight, I, on its horizontal arm, said weight being adapted to be adjusted 20 on said arm, so as to hold the valve open and allow of the free passage of the hot liquid from the boiler to the coils of the pipe E in the reservoir B.

The vertical arm of the lever passes up in- 25 to a stuffing-box, K, which is connected to the reservoir B by a pipe, L, so that when the pressure in the reservoir rises above the desired point it causes the valve G to close and shut off the flow of the hot liquid from the 30 boiler A to the reservoir B through that portion of the pipe E until the vapor-pressure in the latter is reduced to the proper working-point.

In order to maintain under boiler-pressure 35 a constant supply of the weak cooled solution sufficient to absorb the exhaust-vapor from the engine, a pipe, M, is connected to that part of the pipe E which is between the safety-valve and the boiler, so that when the valve G closes 40 and cuts off the supply of hot liquid through the pipe and coil within the reservoir the valve g may be opened and the liquid allowed to flow uninterruptedly from the boiler through the coil e in the cooler F by way of the pipe M. 45 N is a pipe provided with a throttle-valve, h, which connects the reservoir B with the cylinder O, through which pipe the proper amount of vapor is admitted to work the piston of the cylinder, the exhaust-vapor from 50 the cylinder being carried up through the pipe P, where it meets with the cold weak solution from the boiler, as will now be described.

The pipe E, after leaving the cooler F, ex- 55 tends upward some considerable distance above the cylinder, where, by means of a T-joint, it is connected to the pipe Q in a nozzle or contracted portion, i. The pipe P is also connected to the upper end of the pipe Q by 60 means of the elbow-joint k, so that the exhaust-vapor from the cylinder is brought into contact with the cold weak solution from the pipe E, which absorbs the vapor, and is conducted to the jacketed space R of the cylinder, and by which means the cylinder is kept 65 at the proper working temperature by the heat of absorption. If the cylinder is not thus

protected, on account of the low boiling-point of ammonia and the comparatively high temperature of the working-vapor, a very wide 70 range of temperatures is possible. The great depression of temperature within the cylinder consequent upon the expansion of the vapor cools the body of the cylinder to such an extent that a great portion of the heat carried into the cylinder by the vapor is required 75 to restore the cylinder to the proper working temperature. I have found in practice that the vapor entering the cylinder at 195° temperature and let down through the cylinder 80 by expansion is exhausted at 40°, which depression would be further increased by an earlier cut-off within the cylinder. By the above process the body of the cylinder can always be maintained at a temperature of 150°, 85 however low the temperature of the exhaust may be.

I will remark in this connection that the cold weak solution is sprayed into the upper end of the pipe Q under boiler-pressure, and 90 carries with it the exhaust-vapor from the pipe P, said vapor being readily absorbed in the liquid, by reason of its reduced temperature, and by reason of its being sprayed or forced into mechanical union with the vapor 95 by the pressure from the boiler.

S is a pipe of smaller diameter than the pipe E, and communicates therewith by means of the T-joint, the lower end of said pipe S being connected to a pipe, T, leading to the ab- 100 sorber V.

W is a pipe leading from the jacketed space of the cylinder to the absorber V, through which the liquid is passed to the absorber after having done its work in heating the cylinder. 105

As before stated, the exhaust-vapor from the cylinder which has passed up through the pipe P and been mingled with the cold weak solution coming over from the boiler through 110 the pipe E is forced down under pressure into the jacketed space of the cylinder, where it gives off its heat to keep the cylinder at the proper working temperature. This, as a natural consequence, after working for some time, 115 raises the temperature in the jacketed space to such an extent as to revaporize a portion of the absorbed vapor; and in order to prevent the back-pressure of the vapor thus disengaged from interfering with the proper working 120 of the piston I connect the jacketed space of the cylinder with the pipe S, leading to the absorber, by means of the pipe A'. This arrangement enables the vapor formed in the jacketed space to pass out and be brought 125 into contact with the cold weak solution in the pipe S, where the vapor is absorbed and passes down into the absorbing-chamber V. In case a greater amount of cold solution than can pass through the pipe S is required 130 to absorb the vapor from the cylinder, I connect the pipe E with the pipe T by means of the pipe B'. This enables me to bring the requisite amount of cold solution into contact 135

with the vapor from the jacketed space to effect a complete absorption of the vapor. The absorber V is supplied with the requisite amount of water to cool the liquid by means of the pipe f, which also supplies the cooler F. The vapor-liquid, after leaving the absorber V, is forced back into the boiler A or reservoir B, through the pipes C' D', by means of the pump E', the pipes C' and D' being provided with valves a' b', respectively, which enables the operator to admit the solution into either the boiler or the reservoir. This is an important feature of my invention, as it enables the operator to increase or decrease the tension in both boiler and reservoir as occasion may require.

Having thus described my invention, what I claim, and desire to secure by Letters Patent, is—

1. In an aqua-ammonia engine, a boiler for generating the vapor and a dynamical reservoir, such as described, for receiving the vapor from the boiler and supplying it to the cylinder, said reservoir being partially filled 25 with the solution or aqua-ammonia, as set forth.

2. In an aqua-ammonia engine, a liquid-reservoir, such as described, adapted to receive the vapor from the boiler, said vapor being injected into the reservoir below the surface of the liquid contained therein, as set forth.

3. In an aqua-ammonia engine, a boiler for generating the vapor and a dynamical reservoir, such as described, for receiving the vapor, said reservoir being partly filled with aqua-ammonia, the boiler and reservoir being connected by a pipe, C, whereby the quantity of liquid in either the boiler or reservoir is regulated.

4. In an aqua-ammonia engine, a boiler for generating the vapor and a dynamical reservoir, such as described, for receiving the vapor from the boiler, said reservoir being provided 45 with a coiled pipe leading from the boiler, whereby the vapor in the reservoir is superheated, as set forth.

5. In an aqua-ammonia engine, a boiler for generating the vapor, a dynamical reservoir for receiving the vapor from the boiler, said reservoir being provided with a coiled pipe leading from the boiler for superheating the vapor in the reservoir, and a valve located in the path of the pipe leading to and connecting

with the reservoir, whereby the supply of liquid passing through said pipe and the heat in the reservoir is automatically regulated, as set forth.

6. In an ammonia-engine, a boiler for generating the vapor, a dynamical reservoir for receiving the vapor from the boiler, and a pipe leading from the boiler through the reservoir to the exhaust from the cylinder, whereby the exhaust-vapor from the cylinder is absorbed by the weak solution from the boiler under boiler-pressure.

7. In an ammonia-engine the working-cylinder of which is jacketed to receive the exhaust-vapor from the cylinder, a pipe leading from the boiler to the jacketed space of the cylinder, through which the weak solution from the boiler is conveyed to the jacketed space to absorb the exhaust-vapor, whereby the heat of absorption is utilized to maintain a proper working temperature in the cylinder, as set forth.

8. In an ammonia-engine the cylinder of which is jacketed, as described, to receive the exhaust from the cylinder, a pipe leading from the top of the jacketed space to and communicating with the liquid-pipe from the boiler, whereby an induced current is maintained, to free the jacketed space of vapor and to prevent back-pressure on the piston.

9. In an ammonia-engine a boiler for generating the vapor and a dynamical reservoir, such as described, partially filled with aqua ammonia, for receiving and superheating the vapor from the boiler, in combination with the pipe N and cylinder O, as set forth.

10. In an ammonia-engine, the pipe E, having a branch or switch pipe, M, connecting the bent portions of the pipe E outside of the reservoir, in combination with the valve G, whereby a constant boiler-pressure is maintained on the liquid which absorbs the exhaust-vapor from the cylinder when the valve G closes the pipe E, as set forth.

11. The pipes C' and D', provided with the valves a' and b', in combination with the pump E', whereby the liquid can be directed into the boiler or reservoir, as set forth.

In testimony whereof I affix my signature in presence of two witnesses.

JOSEPH H. CAMPBELL.
